UNITED STATES PATENT OFFICE.

J FRANK WILCOMB, OF NORRISTOWN, PENNSYLVANIA, ASSIGNOR, BY MESNE ASSIGNMENTS, TO SPARTAN NEEDLE COMPANY, OF PROVIDENCE, RHODE ISLAND, A CORPORATION OF RHODE ISLAND.

KNITTING-NEEDLE UNIT.

1,391,033.

Specification of Letters Patent. Patented Sept. 20, 1921.

Application filed April 12, 1919. Serial No. 289,691.

To all whom it may concern:

Be it known that I, J. FRANK WILCOMB, a citizen of the United States, and resident of Norristown, Pennsylvania, have invented 5 certain new and useful Improvements in Knitting-Needle Units, of which the following is a specification.

My invention comprises an improved knitting instrument or needle unit designed to 10 perform all the knitting functions of which either latch needles, or spring beard needles, are capable while avoiding the objectionable features of each of these types of knitting needles.

15 The invention also includes the machine organization coöperating with the improved needle unit for carrying on the knitting operation.

The invention is shown in the accompanying 20 drawings in which;

Figure 1 shows the knitting instrument or unit and part of the fabric.

25 Fig. 1^a is a side view of the needle unit illustrating its capacity for operation by hand and showing it in connection with a portion of the fabric being knit.

30 Fig. 2 is a view of the needle unit with the coacting elements thereof in a position and relation assumed by them following the relative position of Fig. 1.

Fig. 3 is a similar view illustrating the 35 next step in the knitting operation.

Fig. 4 illustrates the next step following that of Fig. 3.

35 Fig. 5 illustrates the next step the coacting elements of the needle unit having returned to the position and relation of Fig. 1.

40 Fig. 6 is a view of that one of the coacting members of the needle unit which I designate as the hooked yarn drawing element.

Fig. 7 is a view of the other coacting member of the needle unit which I designate as the loop spreading and hook guarding element and which I also refer to herein as the 45 sheath or quill.

Fig. 7^a is a view of a stop member forming a part of the quill.

Fig. 7^b is an end view of the stop member and quill.

50 Fig. 7^c is a rear view of the quill.

Fig. 7^d is a plan view of the quill blank.

Fig. 7^e is a sectional view of the stem of the hooked yarn drawing instrument showing the groove in the back thereof and the 55 nose of the quill buried therein.

Fig. 8 is a view of a modification of the hooked yarn drawing member of the needle unit.

Fig. 9 is a view of another modification of the hooked member.

60 Fig. 10 is a view of a circular knitting machine partly in section and partly in elevation with a single row of knitting needle units.

Fig. 11 is a plan view of the machine of Fig. 10.

Fig. 12 shows a developed view of the cams for operating the coacting members of the needle unit, this view being diagrammatic in character.

70 In the particular embodiment of the invention which I have chosen for illustrating its characteristics and its mode of operation, but which is not to be regarded as limiting its scope to the specific form shown, a hooked yarn drawing element 1, is employed having a hook 3, a throat 4, a stem, a butt 5 and a shank 6.

75 The hook 3 is made up of the bend at the nose and the extended non-flexible beard, the throat being the reduced part below the hook. Coöperating with this element is what I term, for convenience, but not in a limiting sense, a quill or sheath 2. This in its best form is of channel shape in cross section, having thin parallel side walls receiving slidably between them the hooked yarn drawing element. This quill or sheath 80 is designed to spread the old loop on both sides and over the top of the hook of the yarn drawing element, and it is also designed to guard the hook while the opened or spread loop is moved thereupon for casting off.

85 For the loop spreading action, the quill may assume different formations, but the one illustrated herein presents substantial advantages inherent thereto in that it has a pointed nose 7 lying at the back of the yarn drawing element. Here the loop supported on the throat of the yarn drawing element presents its normal opening in condition to be safely penetrated by the pointed nose to initiate the loop spreading or opening action, which then continues progressively in a direction from the back of the 90 stem of the hooked yarn drawing element 100 toward the front or supported end of the loop as will hereinafter appear. From this nose the edges of the side walls rise at 8 on an incline to the hump or swell 9, which is followed by edges reversely inclined in re-

95

100

105

110

115

spect to the incline at 8, this portion 10 being termed a drop leading to a depression, termed a throat 11. Then comes the stem 12, which connects with higher side walls 13. 5 forming a base portion which terminates with a lateral extension forming the quill butt 14. Between the high walls 13 a block 15 is fixed by rivets 16 and this block is termed a stop. It has a butt portion 10 forming substantially to the butt 14, and it is of less height than the walls 13 to afford a continuation of the channel, of the quill, for receiving the shank of the needle member.

The stop 15 may be brazed, or welded into 15 place, and it may be of any suitable form that will stiffen the walls of the quill. It need not necessarily act as a stop for the butt of the yarn drawing element.

The two members of the needle unit are 20 operated by cams, one for each set of said members, and these cams act on the butts of the members.

Referring to Figs. 1 to 5 which show the needle unit or knitting instrument in the 25 different positions assumed by its members in relation to the knitting plane, (indicated by the line *a—a*) during the knitting operation Fig. 1 shows the unit in its retracted position with the loop hanging in the hook 30 of the yarn drawing member of the unit.

Fig. 2 represents the hooked yarn drawing member as having advanced in relation to the quill to open the hook for receiving the new yarn. Fig. 3 shows the needle member 35 further advanced but followed up by the quill to maintain substantially the same relation to each other, as in Fig. 2, but the quill has passed into the old loop, and this has ridden up the incline 8 over the swell 40 and has lodged in the throat of the quill. The new yarn has been supplied to the throat of the hooked yarn drawing member and the parts are then retracted to the position and relation shown in Fig. 4, the hook 45 thus having been closed by its beard entering between the walls of the swell so that the old loop may be cast, which is done when the parts, continuing their retraction while in the relation of Fig. 4, have reached the position of Fig. 5 which is the same as that 50 of Fig. 1.

As compared with the ordinary latch needles the new needle unit avoids the use of the latch, the rivet on which the latch 55 pivots, the thin walls on either side of the latch, and in a machine using them latch guards, and latch openers are not required and the manufacture of the needle units is simpler than that of latch needles.

60 As compared with spring beard needles the new needle unit avoids the objections due to crystallization of beards, side deflection of beards, fatigue causing "dead" beards, and needle pressers are dispensed with.

65 The new needle unit may be employed in

machines of the latch needle type constructed either for ribbed work with two rows of needles, or flat work of the single row of needle style, with very slight changes in needle operating cams. The needle may be 70 used for stocking knitting, where "picks" are employed to suspend the knitting action of certain needles at intervals. Sinkers may also be used either for ribbed work using two 75 rows of needles, or flat work made on single rows of needles. Provision for dividing the new sunk yarn and the old, or fabric loop, is reduced to a simple, safe, reliable mechanical action, while in the case of spring beard needles "division" of the yarns has heretofore been largely a matter of skillful adjustment by a knitting expert. Deflection sidewise, of needle beards, has always been a cause of trouble with spring beard needles. The new needle has no flexible part liable to 80 side deflection. Crystallization and also deadening of the beards, due to successive depressions by the presser wheels, bars, or the individual "pressers" (whichever is used) is entirely overcome—there is no 90 bending action in any part of the new needle, and presser devices are dispensed with.

The throat of the hooked yarn drawing member is smaller and thinner than that of ordinary needles by just the thickness of the 95 quill walls. The depth and thickness of the quill swell can be exactly the same as like dimensions of standard latch and spring needles... All loops as a matter of course must pass over the largest part of a needle. That is to say over the hook and closed latch of the latch needle. A loop large enough to pass over the hump or swell of the quill will hang on the throat of the hooked yarn drawing member in the form of a loose loop, and a relatively large or normal opening will be exposed at the back of the stem of the yarn drawing member into which the quill nose can pass freely, see Fig. 2. The construction of hook shown in Fig. 9 is illustrated also 100 in Fig. 1^a, where the tip of the hook is shown at 30°.

The following table gives a comparison of my improved needle with that of an ordinary latch needle as to dimensions and 115 length of travel.

Comparison table.

	New hooked member.	New quill.	Reg. needle.	120
Movement	1 (?)	1 (?)	1	
Thick	.090 $\div$ 5=.018	.138 $\div$ 5=.027 ^a	.028 ^b	
Depth	.240 $\div$ 5=.048	.270 $\div$ 5=.054	.055	
Throat	.160 $\div$ 5=.032	.190 $\div$ 5=.038	.035	
Hook	.340 $\div$ 5=.068	None	.072	
Hook and latch	None	.370 $\div$ 5=.074	.078	125

Fig. 8 shows a large bent hook suitable for direct fed machines, where each needle draws its own loop of yarn, and knots or bunches are allowed free passage therethrough. A 130

quill is used with this hooked yarn drawing member but is not shown.

Fig. 9 shows a sinker fed hooked yarn drawing member to be used with a quill of substantially the form above described. The hook of this yarn drawing member is too small to allow two yarns to dispute their right to first place *i. e.*, against the inner side of the nose—that is, the tip 30—of the hook. 5 No rendering of yarn in the needle should be allowable in any sinker fed machine. The sinkers supply the yarn and the needles simply draw the supply into the fabric as in ordinary practice. If two, or more, yarns 10 are held snugly by a needle member, such as illustrated in Fig. 9, and not allowed to render or curl out of place, plating becomes a simple matter, and this is accomplished by the hooked member shown. The sinker is 15 shown at 23^a.

Referring to Fig. 12 the cam path for the butts of the hooked yarn drawing members is shown at 24; that for the butts of the quills at 25, and that for the friction jacks 20 25 at 26; when these are employed, at 26'. In Fig. 11 the cam path for the web holders 27 is shown at 28. The cams for the quill butts can act thereon to give the quills all their movements. I prefer, however, to let the 30 butts of the hooked yarn drawing elements contact with a portion of the quills for instance the stops, to move the quill for a part of the quill's stroke. The shank of the yarn drawing element is shown as extending 35 through and beyond the quill in order to contact with the friction jack, but it does not need to extend through if the jack is not used.

The quill stem should be of less depth 40 than the stem of the hooked element so that the yarn loops will slide on the hooked member rather than on the thin walls of the quill, also when the needle is employed in a machine, spring bands (in the case of circular machines) may be employed to hold 45 the hooked yarn drawing elements down in the quill and hold both in the bottom of a needle groove, in the same way that spring bands are ordinarily used in machines of the 50 circular type. If the needle is used in straight bar machines of the Lamb type, the gib plates of the machine should contact the stem of the hooked yarn drawing element so as to hold it down close to the bottom of the 55 quill stem at all times. The wear also, of the spring bands or the gib should come on the needle stem and not on the thin walls of the quills.

In Fig. 6 I have shown the stem of the 60 hooked yarn drawing element having a V-groove 29 at the back and the quill point 7 (Fig. 7) is bent so as to fall into this groove, not necessarily contacting either side or bottom of the groove, but the point of the quill 65 fits into the groove below the outer surface

of the stem sufficiently to insure the passage of the quill point between the yarn fibers of the loop and the stem. It is not necessary in all cases, if any, that the quill point should extend into the stem. My hooked 70 yarn drawing member at the throat is of less depth and thickness than is customary with needles of a corresponding gage in either spring or latch needle machines. The quill in thickness and depth at the swell 75 corresponds to the largest loop expanding portion of an ordinary needle, as, for instance, the closed barb of a spring needle or the closed latch and hook of a latch needle and any loop of yarn large enough to pass 80 safely over the closed beard, closed latch or the swell of the quill will hang loosely on the throat of my reduced stem of my yarn drawing member, leaving an opening in the loop of considerable size at the back of the 85 needle unit. Into this loop opening back of the needle the quill point can always safely pass, excepting possibly in stocking knitting while making gores or heel pockets, or the selvage needle when making fabrics having 90 selvages and in these instances the opening in the loop has a tendency to be drawn side-wise relative to the yarn drawing member and therefore taut across the back thereof and the groove in the stem and the bent 95 point 7 of the quill are obviously of advantage.

I have found that flattening the back of the stem of the hooked yarn drawing element, that is, taking away the rounded edge 100 of the stem at the back and making the quill point to lie flat against the stem is sufficient to insure the point entering the loop in ordinary knitting practice.

The specific form of my improved knitting needle herein disclosed, having been selected by me as illustrative of the features and principles underlying my invention, is not to be considered in a restrictive sense, the scope of my invention being defined by 105 the appended claims, but I may point out that the specific form shown, enabling penetration of the loop to take place at the back of the needle unit and initiate its spreading or opening here where it is more 110 or less normally open or in condition to allow the quill nose to enter, presents a material advantage in the way of certainty and ease of action and contributes to the utilization of the improved needle for work 115 of the finest gage.

It will be noted that in dividing the old loop from the new yarn for the purpose of allowing the end of the beard to position itself between them as in Fig. 4, the old 120 loop is held in this divided off position by the swell of the quill and while the hooked member is still in movement from its position of Fig. 3 to that of Fig. 4, and this divided position of the old loop is main- 125 130

tained until the point of the hook is fully guarded by the walls of the quill swell.

The method of knitting disclosed herein is claimed in application Serial No. 345,514, 5 filed December 17, 1919, and the combination of the knitting instruments in a rib knitting machine is claimed in application Serial No. 305,473, filed June 20, 1919.

What I claim is:

10 1. A knitting instrument comprising a hooked yarn drawing element, and a loop spreading element, the latter having a point to penetrate the loop at the back of the hooked yarn drawing element, and there 15 initiate the spreading of the loop for casting over the hook, substantially as described.

20 2. A knitting instrument comprising a hooked yarn drawing element and a loop spreading element, the latter having a point to penetrate the loop at the back of the hooked yarn drawing element and having also a formation following said point for spreading the loop at both sides and over the point of the hook of the yarn drawing 25 element, substantially as described.

30 3. A knitting instrument comprising a hooked yarn drawing element, and a loop spreading element, the latter having a point to penetrate the loop at the back of the hooked yarn drawing element and having also a formation following said point for progressively spreading the loop for casting over the hook, substantially as described.

35 4. A knitting instrument comprising a hooked yarn drawing element and a loop spreading element having a nose to penetrate the loop at the back of the yarn drawing element, thereby to initiate the loop preparing action, and inclines rising from 40 said nose at the sides of the yarn drawing element to carry on the spreading of the loop for casting over the hook, substantially as described.

45 5. A knitting instrument comprising a hooked yarn drawing element, and a loop spreading and hook guarding element having the following features; a nose at the back of the yarn drawing element to penetrate the loop, inclines rising from said 50 nose at each side of the yarn drawing element to carry on the spreading of said loop, and guard means at the top of said inclines for receiving the hook and guarding it while the spread loop is moved thereon, substantially as described.

60 6. A knitting instrument comprising a hooked yarn drawing element, and a loop spreading and hook guarding element having the following features; a nose at the back of the yarn drawing element to penetrate the loop, inclines rising from said 65 nose at each side of the yarn drawing element to carry on the spreading of said loop, and guard means at the top of said inclines for receiving the hook and guarding it while

the loop is moved thereon, said guard means comprising the spaced apart walls of the loop spreading element, substantially as described.

7. A knitting instrument comprising a hooked yarn drawing element, and a loop spreading element, the latter being wholly exterior to the yarn drawing element and having a nose to penetrate the loop at the back of the yarn drawing element and an incline formation following said nose to prepare the loop for casting over the hook, substantially as described. 75

8. A knitting instrument comprising a hooked yarn drawing element, and a loop spreading element, the latter having a nose to penetrate the loop at the back of the hooked element, an incline formation following the nose for preparing the loop for casting over the hook, a formation for guarding the hook and an incline formation for dividing the said loop from the new yarn while the point of the hook is moving into its guarded position between said loop and 85 yarn, substantially as described. 90

9. A knitting instrument comprising a hooked yarn drawing element, and a coacting element for preparing the loop for casting off, the latter element having a formation to first engage the loop apart from 95 where it is stressed across the throat of the hooked yarn drawing element and thereafter to spread the loop at both sides and prepare it to pass the point of the hook, substantially as described. 100

10. A knitting instrument comprising a hooked yarn drawing element, and a coacting element for spreading the loop for casting off, the latter element having a formation to first engage the loop apart from 105 where it is stressed across the throat of the hooked yarn drawing element, and thereafter to spread the loop by a progressive action along its sides to prepare it to pass the hook, substantially as described. 110

11. A knitting instrument comprising a hooked yarn drawing element, and a coacting element for spreading the loop for casting off, the latter element having a formation to first engage the loop apart from 115 where it is stressed across the throat of the hooked yarn drawing element, and having inclines at the sides of the hooked element rising from the zone of first engagement with the loop to spread the loop and prepare it to pass the point of the hook, substantially as described. 120

12. A knitting instrument comprising a hooked yarn drawing element, and a coacting element for spreading the loop for casting off, the latter element having a formation to first engage the loop apart from 125 where it is stressed across the throat of the hooked yarn drawing element, and having inclines at the sides of the hooked element 130

rising from the zone of first engagement with the loop to spread the loop and prepare it to pass the point of the hook, said inclines terminating in a swell to guard the hook for 5 the movement of the loop thereupon, substantially as described.

13. A knitting instrument comprising a hooked yarn drawing element, and a loop spreading element exterior to the yarn drawing 10 element and of U-shape in cross section with the base of the U at the back of the hooked yarn drawing element, the walls of said U-shaped member having inclined front edges rising at the sides of the hooked member to spread the loop, and being spaced 15 apart at the top of the inclines to receive and guard the hook between them while the loop moves thereon, substantially as described.

14. A knitting instrument comprising a hooked yarn drawing element, and a loop spreading element exterior to the yarn drawing element and of U-shape in cross section with the base of the U at the back of the hooked yarn drawing element, the walls of 20 said U-shaped member having inclined front edges rising at the sides of the hooked member to spread the loop and being spaced apart at the top of the inclines to receive and guard the hook between them while the loop 25 moves thereon, the side walls of the U-shaped member in rear of the hook guarding portions having a drop to divide the old loop from the new yarn and to guard it from the hook while the latter is moving into its 30 guarded position, substantially as described.

15. A knitting instrument comprising a hooked yarn drawing element, a loop spreading element exterior thereto and having a terminal formation to penetrate the loop 40 hanging on the hooked yarn drawing element, and inclines rising alongside of the hooked yarn drawing element from the loop penetrating formation to spread the loop with a guard at the top of the inclines for 45 receiving the hook to enable the spread loop to be moved thereupon, said guard being followed by a drop in the exterior member to divide the old loop from the new yarn while the point of the hook is moving into guarded 50 position.

16. A knitting or crochet instrument comprising a hooked yarn-drawing element, a loop-spreading element, the loop-spreading element having capacity to spread the loop 55 on both sides of and over the top of the hook of the said yarn-drawing element, the last mentioned element being slidably inclosed between two walls of the loop-spreading element.

60 17. A knitting machine needle composed of two separately slidable elements, one having a stem and a yarn engaging hook, the other being a loop spreading element having a stem and a loop spreading portion, the first 65 mentioned element being slidable between

the walls of the second mentioned unit, both being adapted to lie in and to be separately slidable in a single needle groove of a knitting machine needle carrier.

18. A knitting machine needle comprising two separate elements, one having a hook serving to receive yarn for a new loop, the other having a wall at each side of and outside the first mentioned element with a swell serving to spread the already formed loop to 70 allow the new loop to be drawn through the spread loop and to guard the said formed loop from contacting with the hook of the yarn receiving element, both instruments 75 slidable in a single needle groove of a knitting machine needle carrier.

19. A knitting machine or crochet needle comprising two separate elements, the first element having a stem and a hook and functioning to receive yarn for a loop, and draw 80 said loop through a previously formed loop, the second element having two walls exterior to the first element providing, a loop spreading swell and a throat, said element functioning to spread the said previously formed 85 loop to allow the free passage through it of the hook and new loop, and also to hold the said previously formed loop in a predetermined position to guard it from contacting 90 with or being engaged by the hook of the first element until the said hook is protected by the swell of the second element, the first instrument being slidable between the two 95 walls of the second instrument.

20. A knitting machine or crochet needle 100 comprising two separate members, the first member having a stem and a hook and a butt, the second member having a two walled stem, a pointed nose, a swell, a throat, and a stop in the stem, the first member being slid- 105 able between the walls of the second member and adapted to contact the stop in the second member and to thereby limit the relative movement of the two members and to cause the hook of the first member to 110 register with the swell of the second member, substantially as described.

21. A knitting or crochet needle comprising two separate elements, the first element adapted to receive yarn for a new loop, the 115 second element adapted to pick up a previously formed loop from the stem of the first element to spread the said loop to allow a new loop to be drawn through it, the second element being substantially U-shaped 120 in cross section with the base of the U at the back of the first element and with the first element slidable between the walls of the second element, said second element having a pointed nose adapted to slide along the 125 back of the stem of the first element and pass into the old loop thereon, and inclined walls extending from said pointed nose along which inclined walls the loop may slide without undue abrasive action on the yarn fibers. 130

22. A two element knitting or crochet needle, one element having a yarn hook, a stem, a throat of smaller dimension than the stem and a butt, the other element being 5 a quill substantially U-shaped in cross section, and having the following features: a butt, a stop, a stem, a throat and a swell larger than the hook having inclined walls terminating in a pointed nose, said pointed 10 nose adapted to slide close to the stem of the first element under the throat and to pass into a yarn loop on the first element, the throat and swell serving to hold the loop in a definite position, the hooked element being 15 slid able inside the quill and adapted to contact the stop, thereafter both units being operative as one unit to complete the loop forming movement, substantially as described.
23. A knitting machine needle comprising two distinct elements, one inside the other and adapted to operate independently and simultaneously at times in a single groove of a knitting machine needle carrier, one element 20 having a yarn hook, a stem, a groove in the back of the stem, and the other element being a quill having two walls between which the hooked element instrument is slid able, the quill having a pointed nose to enter 25 the said groove, inclined walls rising from the pointed nose terminating in a swell, said swell being higher in cross section than the hook, said pointed nose adapted to pass into a loop where it is open at the back of the 30 stem, said swell adapted to spread the loop to allow the hook and a new loop to be drawn through it, substantially as described.
24. A knitting machine instrument comprising two separately slid able elements 40 adapted to operate in the same plane, one element having a yarn hook, and a stem, the other element being a quill in which the hooked element may slide and having a stem of substantially U-shape in cross section, 45 having a pointed nose, a swell having two walls higher than the hook, a throat smaller than the swell, the said pointed nose adapted to pass between the yarn loop and the stem, of the first-mentioned element the 50 swell adapted to spread the loop, and the throat adapted to hold the loop in a predetermined position while the hook is entering the swell, said pointed nose, swell and throat, being U-shaped in cross section, substantially 55 as described.
25. A knitting machine sinker fed plating needle comprising two separate units operable in the same plane, independently slid able and simultaneously slid able, at different 60 times in knitting, one of said units having a plating yañ hook bent to such

dimensions as to allow only one strand of 65 yarn to lie against the inner side of the tip of the hook at one time and to the exclusion of another yarn lying in the same plane transversely of the needle stem, the other 70 of said units being a quill shaped instrument operable to expand a previously formed loop to allow the two or more yarns to be drawn through it, substantially as described.

26. A knitting instrument comprising a hooked yarn-engaging element, a quill slid ably inclosing the hooked yarn-engaging element, and of U-shape in cross section, a 75 swell thereon and a stop member between the walls of the quill, to register the hook with the swell, substantially as described.

27. A knitting instrument comprising a hooked yarn-engaging element, a quill slid ably inclosing the hooked yarn-engaging element having a butt, said quill being of substantially U-shape in cross section at its 80 stem and butt and a stop member between the walls of the stem and the butt, substan tially as described.

28. A knitting instrument comprising a hooked yarn-engaging element, a quill slid ably inclosing the hooked yarn-engaging element having a butt and of substantially 85 U-shape in cross section at its stem and butt and a stop member between the walls of the stem and the butt, said yarn engaging member having a shank slid able through the space between the stop member and the back 90 wall of the quill, substantially as described.

29. In combination a hooked yarn drawing member, a quill member having a portion to 100 enter and spread the loop, said quill member being of substantially U-shape in cross section, and a stop member held between the walls of the quill member, the said hook member having a shank slid able in a space between the stop member and the back wall of the quill, substantially as described.

30. A knitting instrument comprising a two walled quill element and a hooked yarn drawing element slid able between the walls of said quill and both adapted to slide in the groove of a knitting instrument carrier, 110 each of said elements having a butt to be engaged by a cam for operating it, said quill having a pointed nose to slide along the back of the hooked yarn drawing element to pass into a fabric loop, each quill also 115 having a swell to spread the said loop and to guard it against engagement with the hook of the yarn drawing element and to direct the said fabric loop onto the hook for casting off, substantially as described.

In testimony whereof, I affix my signature.
J. FRANK WILCOMB.
